E. G. BATES.
BAG-HOLDERS.

No. 180,826.

Patented Aug. 8, 1876.

UNITED STATES PATENT OFFICE.

EDWARD G. BATES, OF CARTHAGE, MISSOURI.

IMPROVEMENT IN BAG-HOLDERS.

Specification forming part of Letters Patent No. **180,826**, dated August 8, 1876; application filed June 3, 1876.

To all whom it may concern:

Be it known that I, EDWARD G. BATES, of Carthage, in the county of Jasper and State of Missouri, have invented a new and valuable Improvement in Bag-Holders; and I do hereby declare that the following is a full, clear, and exact description of the construction and operation of the same, reference being had to the annexed drawings, making a part of this specification, and to the letters and figures of reference marked thereon.

Figure 1 of the drawings is a representation of a front elevation of my bag-holder, and Fig. 2 is a central vertical sectional view thereof. Fig. 3 is a horizontal sectional view of the same.

This invention relates to bag-holders; and the nature of my invention consists in perforated leather straps secured to vertical standards, in combination with buckles for adjusting the suspending devices to bags of different lengths, as hereinafter particularly described.

In the drawings, **A A** designate standards, which support bag-holding devices, and which are provided with feet **a a**, in order that they may rest more securely upon the ground. **B** is a bed-piece for supporting the bottom of the bag. On the inner sides of standards **A A** I secure vertical perforated straps **C C**, preferably constructed of leather, leaving the lower ends **c c** of said straps free from said standards. These ends **c c** catch into buckles **D D**, which are attached to said standards near the lower ends thereof. On said straps **C C** slide

buckles **E E**, which are provided with short stiff straps **e e**, from which project side horns **F F**, which are preferably constructed of wood, and which catch in the mouth of bag **G**, so as to hold the same open while suspending it.

By this means of suspension the bag is held in proper position without perforating or in any way injuring it. By loosening buckles **D D** the device may be adjusted to bags of any width, and by sliding buckles **E E** up or down the device may be adjusted to bags of any length.

Standards **A A**, bed-piece **B**, and feet **a a** may be made detachable, and standards **A A** are braced at their upper and lower ends by detachable hooked bars **H H**.

What I claim as new, and desire to secure by Letters Patent, is—

1. In a bag-holder, the combination of standards **A A**, straps **C C**, buckles **E E**, and hooks **F F**, substantially as and for the purpose set forth.

2. The combination of standards **A A**, straps **C C**, and buckles **D D** with means for suspending the bag, substantially as and for the purpose set forth.

In testimony that I claim the above I have hereunto subscribed my name in the presence of two witnesses.

EDWARD G. BATES.

Witnesses:
